UNITED STATES PATENT OFFICE.

JAMES E. QUINN AND GEORGE I. BRANCH, OF ST. LOUIS, MISSOURI, ASSIGNORS TO INTERNATIONAL SHOE COMPANY, OF ST. LOUIS, MISSOURI, A CORPORATION OF DELAWARE.

LAP-MARKING MACHINE.

Application filed April 1, 1922. Serial No. 548,854.

To all whom it may concern:

Be it known that we, JAMES E. QUINN and GEORGE I. BRANCH, citizens of the United States of America, residents of the city of St. Louis, in the State of Missouri, have invented certain new and useful Improvements in Lap-Marking Machines, of which the following is a full, clear, and exact description, reference being had to the accompanying drawings, forming a part of this specification.

This invention relates generally to lap-marking machines, and particularly to a machine for marking the several sections of which a shoe is composed, so as to guide an operative in stitching said sections together, the main object being to produce a simple and inexpensive machine of this kind which will act upon vamps, quarters and uppers of various sizes and shapes whereby the location of the stitches is indicated on said parts.

Prior to this invention it was the practice to indicate the location of the stitches on the different parts of shoes by hand, an operative being provided with a template which was placed upon one of the shoe parts, said template being utilized as a guide whereby said operative was enabled to indicate the location of the stitches by means of a series of minute perforations placed in the shoe part with a suitable tool.

The machine herein described is intended to supersede the old time-consuming method mentioned above whereby the marking of shoe parts is simplified and the production of shoes expedited.

Fig. I is a plan view of the marking machine, parts of said machine being broken away.

Fig. II is a front elevation of the machine shown in Fig. I.

Fig. III is a section on line III—III of Fig. I.

Fig. IV is a fragmentary section on line IV—IV of Fig. I.

Fig. V is an enlarged fragmentary section of a portion of the clutch-operating mechanism.

Fig. VI is a fragmentary longitudinal section showing the clutch and its associated mechanism.

1 designates the base of the machine

which comprises a top 2 provided with a plurality of supporting legs 3.

Secured to the top 2 of the base of the machine is a plate 4, said plate being preferably formed of metal and being located on said top 2 adjacent to the front edge thereof. The means for securing the plate 4 to the top 2 of the base of the machine comprises a pair of dowels 5, which extend upwardly from said top and into openings formed in the plate 4 (Fig. III), and a hand-operated bolt 6 which passes through said top 2 and into a threaded opening formed in the plate 4 approximately midway between the ends thereof. By this arrangement the hand bolt 6 will clamp the plate 4 tightly against the top 2 and the dowels 5 will overcome any tendency of said plate to swing in an arc of a circle about said bolt 6.

Located on the upper face of the plate 4 is a fiber sheet 7, said fiber sheet being interposed between said plate 4 and a guide member 8. Screws 9 pass through said guide member and said fiber sheet and into said plate 4 whereby said guide member and said fiber sheet are rigidly fixed to the top 2. It may be mentioned here that the guide member 8 serves as a stop to regulate the position of the work being acted on by the machine, and as said guide member is shaped to correspond to the contour of said work, it is necessary, when the shapes of the parts being acted on are changed, to change the guide member. By removing the bolt 6 the plate 4, fiber sheet 7 and guide member 8 may be removed as one unit and replaced by a similar unit having a guide member of the desired shape.

Secured to the top 2 adjacent to the plate 4 is a plate 10, said plate 10 supporting a fiber sheet 11 similar to the fiber sheet 7. The fiber sheet 11 comprises the means for supporting the work before same is moved into position against the guide member 8, said fiber sheets 7 and 11 being in the same horizontal plane whereby said work may be placed on the sheet 11 and moved into position against said guide member.

Located above the plate 4 is a movable head 12 adapted to move vertically on a pair of vertical guide rods 13 extending up-

wardly from the top 2, said guide rods extending through openings 12' in said head.

The means for imparting vertical movement to the head 12 comprises a pair of rods 14 which extend through openings in the top 2, one of said rods being located adjacent to each end of the head 12. Each of the rods 14 is provided with a shoulder 14' which bears against the lower face of the head 12, 10 the reduced portions of said rods above said shoulders passing through openings in said head 12. Springs 15 which surround said reduced portions of the rods 14 are interposed between the top face of head 12 and nuts 16 at the upper ends of said rods 14. Thus it is apparent that tension of the springs 15 may be increased or decreased by the adjustment vertically of the nuts 16 whereby the pressure applied to the work is 20 regulated.

The lower end portions of the rods 14 extend below the top 2 and said lower ends are connected together by means of a rod 17.

Rotatably mounted in suitable bearings 25 forming parts of the base 1 is a drive shaft 18 provided with a pulley 19 whereby said shaft may be rotated to actuate the moving parts of the machine, said drive shaft being provided with a clutch mechanism which 30 will be hereinafter described, whereby the operation of said drive shaft may be controlled by the operator of the machine.

Supported by lugs 20 extending downwardly from the lower face of the top 2 is a pivoted member 21, the forward end of which is provided with an opening through which the connecting rod 17 passes. The rear end of the pivoted member 21 is bifurcated as shown at 21'. Mounted on the drive shaft 18 in such position as to rotate between the prongs of the bifurcated end of the pivoted member 21 is a cam 22, said cam being fixed to and adapted to rotate with said drive shaft 18.

From the foregoing it is apparent that when the drive shaft 18 is rotated, the cam 22 acting on the bifurcated end 21' of the pivoted member 21 will cause the opposite end thereof to move upwardly and downwardly, and because the head 12 is connected to the outer end of said pivoted member 21 by means of the rods 14 and the connecting rod 17, said head will likewise be moved upwardly and downwardly.

Fixed to the under side of the head 12 is a plate 23 provided with a plurality of downwardly extending piercing pins 24. The plate 23 is secured to the head 12 through the medium of a pair of dowels 25, similar to the dowel 5 which aid in retaining the plate 4 in place, and a hand-operated bolt 25' similar to the hand-operated bolt 6. This arrangement for securing the plate 23 to the head 12 permits the ready removal of said plate when it is desired to replace same with

a plate designed to operate on a differently shaped shoe part.

Secured to the top 2 of the base of the machine at the ends of the plate 10 are grooved guideways 26 which receive a guard 27 in 70 the form of a comparatively heavy sheet of glass. The grooves in said guideways terminate at the point indicated by the reference character 27' whereby a space between the lower edge of the guard 27 and the top face 75 of the fiber sheet 11 is maintained which is high enough to permit the operator to pass the work therethrough to the marking mechanism of the machine, but will not admit the fingers of the operator, whereby the danger of said operator's fingers coming into contact with the piercing pins 24 is eliminated. The guard is made of glass so as not to interfere with the operator's view of the working parts of the machine. 80

The clutch mechanism whereby the operator may control the operation of the machine comprises an extension 28 formed on the pulley 19, said extension being provided with an annular groove 29 within which an integral lug 30 is located. The pulley 19 and the extension 28 are loosely mounted on the drive shaft 18. Fixed to the drive shaft adjacent to the extension 28 is a clutch member 31, said member 31 being provided with an enlarged portion 32 in which is formed a recess 32' into which the extension 28 projects. The clutch member 31 is provided with a pivoted member 33 provided with an end 33' adapted to engage the lug 30, the end of said pivoted member opposite to the lug-engaging end being acted upon by a spring 34 which tends to throw the lug-engaging end 33' of said pivoted member into engagement with said lug 30. 90

Located above the clutch member 31 is an arm 34 pivoted to the top 2 at the point indicated by the reference character 35, said arm being provided with a spring 34' tending to retain a friction roller 36 located at an end thereof in contact with the pivoted member 33. 100

Located in the top 2 adjacent to an end of the pivoted arm 34 is a guide member 37 in the form of a rod circular in cross section, which is provided with a continuous groove 37' throughout its length, said guide being secured in an opening in said top 2 and extending downwardly therefrom. Mounted in the groove 37' of the guide member 37 is a catch 38, said catch being provided with a shoulder 38' adapted to engage an end portion of the pivoted arm 34. Located within the groove 37' in the guide member 37 is a leaf spring 39, said leaf spring bearing against said catch 38 whereby same is held in contact with the end of the pivoted arm 34 when said arm is in its uppermost position. Pivoted to the lower end of the catch 38 is a rod 40, said rod be- 110

ing connected to a suitable foot-pedal (not shown). To prevent the catch 38 being drawn entirely from the groove in the guide member 37 we provide a retaining ring 41 which surrounds said guide member at a point adjacent to its lower end. Thus when the catch 38 has been drawn downwardly to the limit of its movement, the shoulder 38' will contact with the retaining ring 41 to prevent said catch from being moved further.

In the operation of the device, assuming that the properly shaped guide member 8 and the proper plate 23 are in place on the machine, and the operator places a shoe part in position against said guide member 8. If said shoe part be the left section of a shoe upper, said shoe part would be placed with its curved portion contacting with the similarly curved portion at the right of the guide member 8, and if it be the right section of a shoe upper it would be placed with its curved portion contacting with the curved portion at the left of the guide member 8. The operator would then depress a foot-pedal whereby the rod 40 is drawn downwardly and the forward end of the pivoted arm 34 would be moved downwardly by the shoulder 38', on the catch 38, thus raising the opposite end of the pivoted arm 34 against the action of the spring 34'. The pulley 19 and the extension 28 are constantly driven, and when the end of the pivoted arm 34 which is provided with the roller 36 is moved upwardly away from the member 33, the spring 34' will cause the end of said member 33 against which it bears to move outwardly, thereby causing the end 33' thereof to be engaged by the constantly rotating lug 30, whereby said member 33 and the clutch member 31 by which it is supported will be carried around by said lug, and because said clutch member 31 is secured to the drive shaft 18 said drive shaft will be likewise rotated. Upon the rotation of the shaft 18 the rods 14 will be drawn downwardly by the cam 22 acting on the pivoted member 21, whereby the piercing pins 24 are caused to perforate the shoe part in place on the machine.

The springs 15 at the upper ends of the rods 14 eliminate the necessity of regulating the stroke of the head 12 so that the piercing pins 24 will move just far enough to perforate the work, because if the rods 14 continue to move downwardly after said piercing pins had come into contact with the fiber plate 7, said piercing pins would not be driven into said fiber plate, as the excess movement of said head would be taken up by said springs 15.

The function of the catch 38 is to compel a downward movement of the pivoted arm 34 for every operation of the machine, the shoulder 38' drawing the pivoted arm 34

downwardly until the end of said pivoted arm passes from beneath said shoulder due to the fact that said arm end moves on an arc of a circle, the center of which is the point 35. When the end of the arm 34 passes from beneath the shoulder 38' the spring 34' will return said pivoted arm to its original position, thereby disengaging the clutch and the rod 40 with the catch 38 attached thereto will be returned to its uppermost position by a coil spring, which is not shown in the drawing but which may be arranged in any convenient manner, so that when pressure is removed from the foot pedal associated with said rod 40 said rod will move upwardly.

From the foregoing it is plain that any of the sections which compose the upper portion of a shoe may be marked by the machine herein described, it being only necessary to attach the properly shaped marking plate and guide unit thereto.

We claim:

1. A lap-marking machine comprising a work support, means for regulating the position of the work on said work support, a head movable relative to said work support, a marking plate provided with piercing pins removably secured to said movable head, said piercing pins being secured to said marking plate and being arranged in fixed positions relative thereto, means for actuating said movable head and resilient means whereby said actuating means and said movable head are connected together.

2. A lap-marking machine comprising a work support, means for regulating the position of the work on said work support comprising a removable guide member, a head movable relative to said work support, a marking plate provided with piercing pins removably secured to said movable head, said piercing pins being secured to said marking plate and being arranged in fixed positions relative thereto, means for actuating said movable head and resilient means whereby said actuating means and said movable head are connected together.

3. A lap-marking machine comprising a base, a work support on said base a portion of which is readily removable therefrom, said removable portion of said work support being provided with a guide member for regulating the position of the work on said work support, a head movable relative to said work support, a marking plate provided with piercing pins removably secured to said movable head, said piercing pins being secured to said marking plate and being arranged in fixed positions relative thereto, and means for actuating said movable head.

4. A lap-marking machine comprising a base, a work support on said base a portion of which is readily removable there-

from, said removable portion of said work support being provided with a guide member for regulating the position of the work on said work support, a head movable vertically relative to said work support, guides on which said movable head is mounted, a marking plate provided with piercing pins removably secured to said movable head, said piercing pins being secured to 10 said marking plate and being arranged in fixed positions relative thereto, and means for actuating said movable head.

5. A lap-marking machine comprising a base, a work support on said base a portion of which is removably secured thereto, fastening means including dowel pins for securing said removable portion of said work support to said base, said removable portion of said work support being provided with a guide member for regulating the position of the work on said work support, a head movable vertically relative to said work support, guides on which said movable head is mounted, a marking plate provided with piercing pins secured to said movable head, said piercing pins being secured to said marking plate and being arranged in fixed positions relative thereto,

fastening means including dowel pins for securing said plate to said movable head, 30 and means for actuating said movable head.

6. A lap-marking machine comprising a base, a work support on said base a portion of which is removably secured thereto, fastening means including dowel pins 35 for securing said removable portion of said work support to said base, said removable portion of said work support being provided with a guide member for regulating the position of the work on said work support, a head movable vertically relative to said work support, guides on which said movable head is mounted, a marking plate provided with piercing pins secured to said movable head, fastening means including 40 dowel pins for securing said plate to said movable head, means including vertically movable rods for actuating said movable head, and resilient connecting means for connecting vertically movable rods to 50 said movable head.

In testimony that we claim the foregoing we hereunto affix our signatures.

JAMES E. QUINN.
GEORGE I. BRANCH.
